(57) **CLAIM**

The ornamental design for a bird house, as shown.

DESCRIPTION

FIG. 1 is a perspective view of a bird house showing my new design;

FIG. 2 is a front view thereof, the rear view is identical;

FIG. 3 is a bottom view thereof;

FIG. 4 is a right-side view thereof;

FIG. 5 is a left-side view thereof; and,

FIG. 6 is a top view thereof.

The application relates to the design of a bird house designed to accommodate birds. The bird house has two levels, each level having circular openings and a rail running across the front of the circular openings, angled out at approximately 45 degrees. The top of the bird house has a pitched roof and two rails running the length of the top and extending over the edge at both ends of the roof. The bottom of the bird house has a rectangular plate with four buttresses connecting the rectangular plate to a square pole. The broken away line on the square pole of FIGS. 1, 2, 4, and 5 represents a portion of the pole that extends beyond the drawings.

The unique design and appearance of this device are illustrated in the drawings.
